RAILWAY SIGNALING

Filed April 22, 1929

UNITED STATES PATENT OFFICE

CHARLES W. BELL, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY SIGNALING

Application filed April 22, 1929. Serial No. 356,985.

My invention relates to railway signaling, and particularly to signaling of the type involving manually controlled light signals.

One feature of my invention is the provision of novel and improved means for controlling a light signal in such manner that a positive more restrictive indication is given when a less restrictive indication should be given and the lamp for giving such less restrictive indication has failed. Another feature of my invention is the utilization of the "light-out" relays commonly employed in connection with light signals for giving an indication at the point of control to show whether or not the signal has responded to a movement of the controlling lever.

I will describe one form of signaling apparatus embodying my invention, and will then point out the novel features thereof in claims.

The accompanying drawing is a diagrammatic view showing one form of signaling apparatus embodying my invention.

Referring to the drawing, the reference character S designates a light signal comprising two groups of electric lamps E and F. The first group E consists of a proceed lamp G¹, a caution lamp Y¹, and a stop lamp R¹. The second group F comprises a caution lamp Y² and a stop lamp R². The signal also includes an auxiliary stop lamp R³, which lamp, however, does not enter into the present invention.

The lamps of the first group E are controlled by a home relay H¹ and a distant relay D, whereas the lamps of the second group F are controlled by a home relay H². The relays H¹ and H² are in turn controlled by manually operable levers L¹ and L², which levers are usually incorporated in an interlocking machine.

Associated with the proceed lamp G¹ is a light-out relay X¹. A similar relay X² is associated with the caution lamp Y¹, and another similar relay X³ is associated with the caution lamp Y².

Each lever L has a normal position, and is movable to either the left or the right from such normal position. The apparatus which is controlled by these levers when they are

moved to the right is not shown in the present application, and so for purposes of the present specification I will refer to the middle position of each lever as the normal position, and to the left-hand position of each lever as the reverse position.

Home relay H¹ is provided with a circuit which passes from terminal B of a suitable source of current, through contact 16 of lever L¹, and the winding of relay H¹ to terminal O of the same source of current. Contact 16 is closed when lever L¹ is in the reverse position, but open when the lever is in the normal position, and so it follows that relay H¹ is energized when and only when lever L¹ is in the reverse position.

The distant relay D is provided with a circuit which includes a front contact 1 of relay H¹. This circuit will also include other contacts controlled in accordance with traffic conditions, which contacts are not shown in the drawing, because they form no part of my present invention.

Home relay H² is provided with a main circuit which passes from terminal B, through contact 17 of lever L², back point of contact 4 of home relay H¹, and the winding of relay H² to terminal O. Contact 17 is closed when and only when lever L² is in the reverse position, and, consequently, it follows that when relay H¹ is de-energized relay H² will be energized or de-energized according as lever L² is in the reverse or the normal position. The relay H² is provided with an auxiliary circuit which will be explained hereinafter.

Assuming that lever L² is in the normal position, and that lever L¹ has been reversed so that relay H¹ is energized, then if distant relay D is also energized, the proceed lamp G¹ will be lighted, the circuit being from terminal B, through the front point of contact 2 of relay H¹, front point of contact 18 of relay D, winding of light-out relay X¹, and lamp G¹ to terminal O. If, however, relay D is de-energized while relay H¹ is energized, lamp Y¹ will be lighted, the circuit being from terminal B, through the front point of contact 2 of relay H¹, back point of contact

18 of relay D, winding of relay X², and lamp Y¹ to terminal O.

When relay H¹ is de-energized, stop lamp R¹ is lighted, the circuit being from terminal B, through the back point of contact 2 of relay H¹, an impedance 11, the lamp R¹ to terminal O.

When relay H² is de-energized, stop lamp R² is lighted, the circuit being from terminal B, through the back point of contact 5 of relay H², an impedance 13, and lamp R² to terminal O. When relay H² is energized, however, lamp Y² is lighted, the circuit being from terminal B, through the front point of contact 5 of relay H², winding of relay X³, and lamp Y² to terminal O.

I will now assume that relays H¹ and D are energized, that relay H² is de-energized, and that lamp G¹, which should be lighted, is burned out. Current will then flow from terminal B, through the front point of contact 2 of relay H¹, back contact 6 of relay X¹, winding of relay X², and lamp Y¹ to terminal O. If, under the conditions last specified, lamp Y¹ is also burned out, then lamp Y² will become lighted. In order to accomplish this, relay H² will first become energized by virtue of a circuit which passes from terminal B, through back contact 7 of relay X¹, back contact 9 of relay X², front point of contact 4 of relay H¹, and the winding of relay H², to terminal O. Relay H² being energized, lamp Y² will be lighted by virtue of the circuit previously traced, which circuit includes the front point of contact 5 of relay H² and the winding of relay X³. At the same time, lamp R¹ will be lighted by a circuit which passes from terminal B, through the front point of contact 2 of relay H¹, back contact 6 of relay X¹, back contact 8 of relay X², front contact 3 of relay H¹, impedance 11, and lamp R¹ to terminal O.

Lever L¹ is provided with an indication lamp A¹, and lever L² is provided with a similar indication lamp A². These lamps are controlled by back contacts of the light-out relays X¹, X² and X³. The circuit for lamp A¹ is from terminal B, through back contact 7 of relay X¹, back contact 9 of relay X², back contact 10 of relay X³, reverse contact 14 of lever L¹, and lamp A¹, to terminal O. The circuit for lamp A² is the same as the circuit for lamp A¹, except that it includes reverse contact 15 of lever L² instead of reverse contact 14 of lever L¹.

When levers L¹ and L² are in their normal positions, both lamps A¹ and A² are extinguished, because their circuits are opened at lever contacts 14 and 15, respectively. When lever L¹ is reversed, lamp A¹ will become lighted until either signal lamp G¹ or Y¹ becomes lighted, whereupon the circuit for indication lamp A¹ will be opened at one of the light-out relay contacts 7 or 9. When lever L² is reversed, lamp A² will become

lighted until signal lamp Y² becomes lighted, whereupon lamp A² will be extinguished because its circuit will be opened at back contact 10 of relay X³. Assuming that lever L¹ has been reversed, and that both lamps G¹ and Y¹ are burned out, and further assuming that lamp Y² becomes lighted, as explained hereinbefore, lamp A¹ will immediately become extinguished because its circuit will be opened at back contact 10 of relay X³.

In actual practice, the circuits for relays H¹ and H² will as usual include elements whereby these circuits become opened when a train passes signal S, which elements are omitted from the drawing because they form no part of my present invention. Assuming that one of the proceed or caution lamps of signal S has been lighted, due to the reversal of one of the levers L¹ or L², then when a train passes the signal, thereby de-energizing relay H¹ or H², the indication lamp A¹ or A² will become lighted, thereby indicating that the lever is not in the position corresponding to the indication given by the signal. Restoration of the lever to its normal position, will, of course, result in the extinguishing of the associated indication lamp A. If lever L¹ is moved to the reverse position and all three of the lamps G¹, Y¹ and Y² fail to respond, indication lamp A¹ will remain lighted, thereby informing the operator that the signal has not responded to the lever movement. The same thing is true of indication lamp A² in the event that lamp Y² fails to respond to a reversal of lever L².

Lamp R³ of signal S is continuously lighted, the circuit being from terminal B, through an impedance 12, and lamp R³ to terminal O.

The purpose of the impedances 13, 11 and 12 in the circuits for the stop lamps R, is to limit the flow of current to these lamps in the same manner that the flow of current to the lamps G and Y is limited by the associated lightout relays X¹, X² and X³.

Although I have herein shown and described only one form of signaling apparatus embodying my invention, it is understood that various changes and modifications may be made therein within the scope of the appended claims without departing from the spirit and scope of my invention.

Having thus described my invention, what I claim is:

1. In combination, a railway signal comprising a less restrictive lamp and a more restrictive lamp, a manually operable lever having normal and reverse positions, a circuit for said less restrictive lamp controlled by a reverse contact of said lever and including the winding of a relay, means for lighting said more restrictive lamp when the reverse contacts of said lever are closed and a back contact of said relay is closed, an in-

- dication lamp associated with said lever, and a circuit for said indication lamp including a back contact of said relay and a reverse contact of said lever.
5. In combination, a railway signal comprising a plurality of electric lamps, a manually operable lever having normal and reverse contacts, a relay associated with each lamp, a circuit for each lamp including the 70 winding of the associated relay, means operating when the reverse contacts of said lever are closed to close one or another of said lamp circuits depending on other conditions and on the conditions of the lamps themselves, an indication lamp associated with said lever, and a circuit for said indication lamp including in series a back contact of each said relay and a reverse contact of said lever, whereby when said lever is in the reverse position said indication lamp is extinguished if any one of said signal lamps is lighted but is lighted if all of said signal lamps are extinguished.
3. In combination, a railway signal having a first group of lamps and a second group of lamps, the first group comprising a proceed and a caution as well as a stop lamp, and the second group comprising a caution lamp, a home relay and a distant relay for said 90 first group, a home relay for said second group, a light-out relay for each of said proceed and caution lamps, a first and a second manually operable lever each having a normal and a reverse position, means for energizing the first home relay when and only when said first lever is in the reverse position, a circuit for said distant relay controlled by a front contact of said first home relay, a circuit for the proceed lamp of said 95 first group including a front contact of said first home relay and a front contact of said distant relay as well as the associated light-out relay, a main circuit for the caution lamp of the first group including a front contact of said first home relay and a back contact of said distant relay as well as the associated light-out relay, an auxiliary circuit for said caution lamp of the first group including a front contact of the first home relay and a back contact of the light-out relay for the proceed lamp as well as the winding of the light-out relay for the caution lamp of the main group, a main circuit for said stop lamp including a back contact of said first 100 home relay, an auxiliary circuit for said stop lamp including in series a back contact of each light-out relay for the main group of lamps and a front contact of said first home relay, a main circuit for said second home relay including a reverse contact of said second lever and a back contact of said first home relay, an auxiliary circuit for said second home relay including in series a back contact of each light-out relay for the main group of lamps, and a front contact of said 105 first home relay, a circuit for the caution lamp of the second group including a front contact of the second home relay and the winding of the associated light-out relay, an indication lamp associated with each lever, 110 and a circuit for each indication lamp including in series a back contact of each light-out relay and a reverse contact of the associated lever.
4. In combination, a railway signal comprising a first group of lamps and a second group of lamps, a first home relay for controlling the lamps of said first group, a second home relay for controlling the lamps of said second group, light-out relays associated with the lamps of said first group, a first and a second manually operable lever each having normal and reverse positions, means for energizing said first home relay when and only when said first lever is in the reverse position, 115 means for energizing said second home relay when said second lever is in the reverse position provided that said first home relay is de-energized, and auxiliary means for energizing said second home relay when said first home relay is energized and said light-out relays are de-energized.
5. In combination, a railway signal comprising a first group of lamps and a second group of lamps, a first home relay for controlling the lamps of said first group, a second home relay for controlling the lamps of said second group, light-out relays associated with the lamps of said first group, a first and a second manually operable lever each having normal and reverse positions, means for energizing said first home relay when and only when said first lever is in the reverse position, a main circuit for said second home relay including a reverse contact of said second lever and a back contact of said first home relay, and an auxiliary circuit for said second home relay including in series a back contact of each of said light-out relays and a front contact of said first home relay.
6. In combination, a railway signal comprising a first group of lamps and a second group of lamps, a first home relay for controlling the lamps of said first group, a second home relay for controlling the lamps of said second group, light-out relays associated with the lamps of said first group, a first and a second manually operable lever each having normal and reverse positions, means for energizing said first home relay when and only when said first lever is in the reverse position, 120 means for energizing said second home relay when said second lever is in the reverse position provided that said first home relay is de-energized, auxiliary means for energizing said second home relay when said first home relay is energized and said light-out relays are de-energized, an indication lamp associated with each lever, and a circuit for each indication lamp including in series a back contact of said 125 first home relay, a circuit for the caution lamp of the second group including a front contact of the second home relay and the winding of the associated light-out relay, an indication lamp associated with each lever, and a circuit for each indication lamp including in series a back contact of each light-out relay and a reverse contact of the associated lever.

tact of each of said light-out relays and a reverse contact of the corresponding lever.

7. In combination, a railway signal having a first and a second group of lamps, each group comprising a less restrictive and a more restrictive lamp, a first and a second home relay for said first and second groups of lamps respectively, a first and a second manually operable lever each having a normal and a reverse position, a light-out relay associated with each less restrictive lamp, means for energizing the first home relay when and only when the first lever is in the reverse position, means for energizing the second home relay when the second lever is in the reverse position provided that the first home relay is de-energized, auxiliary means for energizing the second home relay when the first home relay is energized and the light-out relay for the first group of lamps is de-energized, an indication lamp associated with each of said levers, and a circuit for each indication lamp including in series a back contact of each light-out relay and a reverse contact of the associated lever.

In testimony whereof I affix my signature.

CHARLES W. BELL.
